JULY 5.

UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

OIL-CUP.

1,317,368.

Specification of Letters Patent. Patented Sept. 30, 1919.

Application filed April 10, 1919. Serial No. 289,033.

To all whom it may concern:

Be it known that I, AUGIE L. HANSEN, a citizen of the United States, and a resident of Evanston, in the county of Cook, State of Illinois, have invented certain new and useful Improvements in Oil-Cups, of which the following is a specification.

My invention relates to oil cups and particularly to that class comprising an oil containing or cup part and a nipple part for supporting the cup part on the mechanism to be lubricated.

My invention is of particular utility in connection with oil cups in which the nipple part extends at right angles to the cup or oil containing part. The usual construction has been to extend the nipple end through one wall of the cup and secure it in place as by brazing. This construction is not very practical as it does not take much of a blow on the cup to tear it from the nipple or to disconnect it sufficiently to permit leakage. The main object of my invention is therefore, to provide improved and more practical connection between the cup part and the nipple part so that the cup will be rigidly secured to and supported by the nipple part.

Another object of my invention is to provide improved closure construction for the cup, to protect the cup against the entrance of dirt, dust, moisture, etc., and to permit the closure to be readily opened for the charging in of oil.

The above and other features of my invention are disclosed in the construction shown on the accompanying drawing in which—

Figure 1 is a side elevational view,

Fig. 2 is an end elevational view,

Fig. 3 is a sectional view on plane 3-3,

Fig. 2,

Fig. 4 is a sectional view on plane 4-4,

Fig. 1.

The device shown comprises the cylindrical oil container or cup part 5, which may be drawn up from a single piece of sheet metal, and the supporting or nipple post 6. The supporting post comprises the outer threaded section 7, the intermediate polygonal section 8 and the inner cylindrical section 9. By means of the threaded outer section 7 the post may be secured to the mechanism to be lubricated, turning of the post 55 to secure it in place being facilitated by the

wrench receiving polygonal section 8. The inner cylindrical section 9 of the post extends through the opening 10 in the side wall of the cup part 5 and extends diametrically across the cup interior into abutting engagement with the opposite wall, the reduced extension 11 primarily at the inner end of the post extending through the hole 12 in the cup part wall and being then riveted over to form the locking flange 13 for securing the post and the cup part together. Preferably the hole 12 is polygonal and the rivet end 11 cylindrical so that when this end is upset and riveted the metal thereof will fill in the polygonal hole and thus rigidly lock the post against turning axially with reference to the cup part. To seal the connection between the cup part and the post, solder may be run into the joint between the post and the cup part wall.

To further increase the rigidity of connection between the cup part and the supporting post the cup bottom may be given the diametrically extending semi-circular downward deflection 14 to form a semi-circular pocket for intimately receiving the cylindrical inner end 9 of the post 6, and solder may then be run down between the sides of the post and the adjacent walls of the cup to further secure the post and cup part together and to thoroughly seal the cup against leakage.

The post has the axially extending outlet bore 15 and the post is slotted transversely to form the connecting passageway 16 between the cup and the bore so that oil may freely flow from the cup part through the post and to the mechanism to be lubricated.

With the above construction the cup part and the post are most intimately connected together and under ordinary conditions of usage it would be impossible to dislodge the cup on the post or to bend it away therefrom or in any way to loosen it so that leakage might occur. Brazing need not be resorted to, ordinary solder being sufficient with my construction to bind the parts together and to prevent leakage.

Describing now the closure mechanism for the cup, the cup near its upper edge has the annular inner ledge 17 which forms a seat for the supporting ring or band 18. This band is open, its ends 19 and 20 extending parallelly outwardly through the vertical slots 21 and 22 cut in the rear wall of the

cup part between the cup top and the ledge 17. These extending ends 19 and 20 form support for the pivot pin 23 whose outer ends receive the ears 24 and 25 extending downwardly along-side the outsides of the ends from the projecting end 26 of the cover 27. A spring 28 is coiled about the pin 23 between the ends 19 and 20, one end of the spring abutting against the cup wall and 10 the other end abutting against the rear edge of the cover extension 26 so that opening of the cover will be resisted. The ring 18 fits intimately against the inner side of the cup part and preferably extends up to the upper 15 edge of the cup, so as to strengthen the upper part of the cup. To further secure the strengthening ring and to seal the spaces where the ring passes through the slots 21 and 22, solder is run in. This strengthening 20 of the cup at its upper part and the intimate and rigid connection between the cup and the post 6 permits very light sheet metal to be used for forming the cup. The cover 27 preferably has the peripheral flange 28 for extending downwardly a distance along the cup sides, and the lip 29 at the front end of the cover permits the cover to be readily raised by the fingers or by a suitable implement. The spout of an 30 oil can may be applied under the lip and the cover raised and the end of the spout then slipped into the cup to direct oil thereinto from the oil can.

I thus produce a strong, rigid, neat and 35 practical oil cup structure which will stand all sorts of heavy usage without becoming distorted, bent, broken or leaky, and which can be readily opened for the charging in of lubricating oil and whose cover when closed 40 fully protects against the entrance of dirt, dust, moisture, etc.

I do not, of course, desire to be limited to the exact construction and arrangement shown and described as changes are no doubt 45 possible which would still come within the scope of the invention.

I claim as follows:

1. An oil cup comprising a cup part and a supporting nipple post, said post inserted 50 through one wall of and extending transversely through said cup part and rigidly secured to the opposite wall thereof.

2. An oil cup structure comprising a cup part and a supporting nipple post, said post 55 inserted through one wall of and extending entirely through said cup part in contact with the bottom thereof and secured to the opposite wall.

3. An oil cup structure comprising a cup 60 part and a supporting nipple post, said cup part having opposed openings in its side walls, the inner part of said post extending through one of said openings and entirely across said cup, the inner end of said post 65 extending through said other opening and

said end being riveted against the outer side of the cup adjacent said other opening.

4. An oil cup structure comprising a cup part and a supporting nipple post, said cup having a large opening in one side and a 70 smaller opening in the opposite side, the inner part of said post extending through said large opening and entirely across the cup part to abutting engagement with the opposite wall, the end of said post having 75 a reduced section extending through said smaller opening and riveted against the cup wall to secure the post to the cup walls.

5. An oil cup structure comprising a cup part and a supporting nipple post, said post 80 inserted through one wall of and extending into and across the interior of said cup part and riveted at its end to the opposite wall.

6. An oil cup structure comprising a cup part and a supporting nipple post, said post 85 extending into and through the interior of said cup part and projecting a distance beyond a wall thereof, the projecting end being riveted over to secure the cup part to the post.

7. An oil cup structure comprising a cup part and an outlet tube at right angles therewith, said tube extended into and through the interior of said cup part body between the opposite walls thereof and secured to 95 said walls, the interior of said tube communicating with the interior of said cup part.

8. An oil cup structure comprising a cup part and an outlet tube at right angles therewith, said tube extended entirely through 100 said cup part body and the opposite walls thereof and being secured to said walls, there being a communicating passageway between said cup part and the tube.

9. An oil cup structure comprising a cup part and a supporting post at right angles therewith, a transverse pocket in the bottom of said cup part, the inner end of said post 110 extending transversely through the cup part and engaging in said pocket and being secured to the cup part, said post having an outlet passageway therethrough communicating with the interior of the cup part.

10. An oil cup structure comprising an oil 115 cup part and a supporting post therefor, the bottom of said cup part having a pocket extending transversely thereof, the inner end of said post extending into and through said cup and engaging in said pocket, a 120 riveting extension on said post; said cup having an opening in its wall for receiving said riveting extension said extension being riveted over against the exterior of the cup part wall to secure the cup to the post, said post having an outlet passageway therethrough communicating with the interior of the cup part.

11. An oil cup structure comprising a cylindrical cup part and a supporting post 130

- therefor, said cup part having openings in its opposite walls and having a semi-circular depression in its bottom wall, the inner end of said post extending through one of said 5 openings and through said cup part and abutting against the opposite wall and engaging in said depression, a riveting extension on said post extending through said opening and said opposite wall and riveted 10 against the cup exterior to secure the cup part and post together, said post having an outlet passageway therethrough communicating with the interior of said cup part for the flow of oil.
12. An oil cup structure comprising a cup part and a supporting post, said cup part having a large opening in one wall and a smaller polygonal opening in its opposite wall, one end of said post extending through 20 said large opening and across the interior of the cup against the opposite wall thereof, a rivet extension on the end of said post passing through said polygonal opening in the cup part and riveted against the outer 25 wall of said cup part to secure the cup part to the post, said post having an outlet passageway therethrough communicating with the interior of the cup part.
13. An oil cup structure comprising a cup part and a supporting post, said cup part having a large opening in one wall and a polygonal smaller opening in the opposite wall, one end of said post extending through 30 said large opening across the cup interior and against the opposite wall, a cylindrical rivet end on said post extending through said polygonal opening and upset to fill said polygonal opening and to secure said cup and post against relative movement, said 35 post having a passageway therethrough communicating with the interior of the cup part.
14. An oil cup structure comprising a cup part and a supporting post, said cup part having a large opening in one wall and a smaller polygonal opening in the opposite wall, the inner end of said post extending 40 through said large opening and transversely 45 through the interior of the cup part having openings in its opposite walls and having a semi-circular depression in its bottom wall, the inner end of said post extending through one of said openings and through said cup part and abutting against the opposite wall and engaging in said depression, a riveting extension on said post extending through said opening and said opposite wall and riveted against the cup exterior to secure the cup part and post together, said post having an outlet passageway therethrough communicating with the interior of the cup part.
15. An oil cup having adjacent slots in its wall at one side thereof, a ring engaging with the interior of said cup at the mouth thereof and having extensions projecting through said slots to the exterior of the cup, and a cover for the cup hinged on said extension.
16. An oil cup having interior seating projections near the top thereof, a ring seating on said projections and engaged against the inner side of said cup wall, there being adjacent slots extending upwardly through the cup wall above said projections, said ring having extensions projecting outwardly from said slots, and a cover for the cup hinged to said extensions.
17. An oil cup having an internal annular seating ledge a distance below its mouth edge, adjacent slots in the cup wall extending upwardly from said ledge to the top of the cup, a ring inserted in the mouth of said cup and seating on said ledge and having extensions projecting to the exterior through said slots, a cover for the cup hinged on said extensions, and a spring tending to hold said cover closed.
18. An oil cup having adjacent vertical slots at one side, an open ring lining said cup at the mouth thereof, the ends of said ring projecting to the exterior of the cup through said slots, and a cover for the cup hinged on said extensions.

In witness whereof, I hereunto subscribe my name this 8th day of April A. D., 1919.

AUGIE L. HANSEN.
